SWITCH

Paul N. Becka, Lakewood, Ohio, assignor to Tru-Fit
Screw Products Corporation

Application August 25, 1958, Serial No. 757,058

4 Claims. (Cl. 200—87)

The invention relates in general to switches and more particularly to high voltage switches which are adapted for switching on the high voltage side of a transformer.

An object of the invention is to provide a switch having a contactor which is movable into engagement with a leaf spring type of contact.

Another object of the invention is to provide a switch having a contactor which is arcuately movable into engagement with a leaf spring type of contact having a substantially arcuate configuration.

Another object of the invention is to provide a switch having a movable and fixed contact arrangement which can be readily adjusted within limits if misaligned.

Another object of the invention is to provide a switch driven by a solenoid with a linkage between the solenoid core and a movable contactor for moving the contactor in an arcuate path.

Another object of the invention is to provide a switch whereby electrical contact is made by sliding engagement of the contacts in a generally arcuate direction.

Another object of the invention is to provide a switch whereby the construction may be easily varied to get a greater or lesser distance between first and second fixed contacts. This is desirable in high voltage switches where arcs are sometimes obtained between the contacts where high voltages are involved.

Other objects and a fuller understanding of this invention may be had by referring to the following description and claims, taken in conjunction with the accompanying drawings, in which:

Figure 1 is an elevational view of the switch of the present invention; and

Figure 2 is a view of the switch taken generally along the line 2—2 of Figure 1.

The switch of the present invention is particularly adapted for use in switching high voltages such as those encountered, for example, in my copending United States patent application Serial No. 653,705, filed April 18, 1957. The switch of the present invention is shown in Figures 1 and 2 and is indicated generally by the reference numeral 10. The switch includes in combination a plastic mounting bracket 11 having three integral mounting lugs 12 extending therefrom and adapted to receive screws through openings 13 for securing the bracket to a desired structure. Secured to the mounting bracket is a solenoid 16 which includes the usual frame 17, iron laminations 18, windings 19 and a movable core 20. The solenoid is secured to the mounting bracket 11 by means of bolts 22 and nuts 23. The solenoid core 20 is provided with first and second extensions 27 and 28, respectively, secured to the lower and upper portions thereof. A double nut 30 is provided on a threaded end of the first extension 27. A helical spring 32 which has a generally tapered configuration is interposed between the solenoid frame 17 and the double nut 30. The spring 32 serves the purpose of maintaining the core 20 in its lowermost position when the solenoid is de-energized, the spring 32 is compressed and exerts a force tending to move the core downwardly.

2

A pivot support 34 is integrally formed with the mounting bracket 11 and extends forwardly from the bracket in a direction generally opposite to the mounting lugs 12. The pivot support 34 receives a pivot member 35 through an opening therein and the pivot member is maintained in a generally fixed position. A generally L-shaped contactor 37 (Figure 2) is mounted on the pivot member for arcuate movement thereabout. The end portion of the contactor 37 which is mounted on pivot member 35 includes a yoke portion 40 and a sleeve portion 41 which surrounds and turns on that portion of the pivot member just outwardly of where the pivot support 34 terminates. A nut 42 provides end bearing for the sleeve portion 41. The other end portion of the contactor 37 extends in a direction generally ninety degrees removed from the pivotally connected end portion and provides electrical connection between different electrical circuits upon movement thereof. This end portion is made up of a double membered construction with the members being spot welded together, as at 45. An arm 48 is integrally formed with the movable contactor 37 and extends laterally outwardly from the point of pivotal connection of the movable contactor 37.

Connection means are provided for connecting the movable contactor 37 to the movable solenoid core 20 so that the generally straight line movement of the core is transmitted to arcuately move the contactor 37. The connection means includes a plastic insulating member 50 which has upper and lower end portions. The upper and lower end portions are provided with slots 52 and 53, respectively. The slot 52 receives the second extension 28 which extends from the solenoid and is maintained in the slot and secured to the insulating member 50 by means of a pin 55. An arcuately shaped connecting link 56 is provided which has first and second end portions 57 and 58, respectively. The first end portion 57 of the link resides in the slot 53 of the insulating member 50 and is pivotally secured therein by means of a pin 60. The second end portion 58 of the link 56 is pivotally secured to the arm 48 by means of another pin 61.

First and second contact assemblies 63 and 64, respectively, are provided and are secured to the mounting bracket 11 by means of bolts 65 and nuts 66. Each of the contact assemblies 63 and 64, respectively, comprise an electrically conductive mounting portion 68 which includes a transversely extending finger 69 which bears against the mounting bracket 11. The contact assemblies also include a contact portion 70 which is secured to the mounting portion 68 by rivets 71 and has a portion 76 which is arcuate in configuration and which lies in the path of travel of the L-shaped contactor 37.

In operation, the device in the normally de-energized condition assumes the position shown in the full-line drawing of the Figures 1 and 2. Upon energization of the solenoid windings 19 through leads 72 and 73, the movable core 20 moves in an upward direction. This causes the spring 32 to be compressed and also causes the second extension 28 and the insulating connection member 50 to travel in an upward direction. This causes the link 56 to move the arm 48 which in turn causes the generally L-shaped contactor 37 to move from the position shown in the full-line drawing to the dot-dash line position 74. The bolts 65, as well as securing the first and second contact assemblies in position, also act as terminals for providing electrical connection to different electrical circuits. The end portion 75 of the pivot member 35 also acts as a terminal for providing electrical connection to the movable contactor 37. As a result, in the full-line drawing position of Figure 1, the contactor 37 makes electrical connection between

the terminal 75 and the terminal 65 of the second contact assembly 64 and to the associated electrical circuit which is not shown. In the dot-dash position 74 electrical connection is made between the terminal 75 and the terminal 64 of the first contact assembly 63 and its associated electrical circuit which also has not been shown. In this manner, electrical connection is alternately made and broken between the above referred to electrical circuits.

It will thus be seen that a switch construction has been provided wherein the movable contactor travels in an arcuate direction into a leaf spring type of fixed contact which also has a generally arcuate configuration. The fixed contact which engages with the movable contactor as mentioned is made of a leaf spring-like material which can be bent by hand to assume various positions within limits and which maintains this position and also its resilient spring-like quality. The contacts of the herein disclosed switch can thereby be bent to compensate for wear if such is the case or may be easily bent to make good contact with the movable contactor in the event the same is misaligned for some reason. The arcuate movement is imparted to the movable contactor through a linkage which has been described hereinabove. The construction and arrangement of the movable contactor and fixed contactor is such that a sliding engagement is made therebetween which provides good electrical connection. The construction of the switch is such that a greater or lesser distance may be obtained between the fixed contacts in the event that such is desirable, for example, a greater or lesser voltage being utilized or if it is desired to make contact sooner or later. The contact portion 70 of either of the contact assemblies may be changed with little difficulty or the entire contact assemblies can be replaced quickly and at little expense.

Although this invention has been described in its preferred form with a certain degree of particularity, it is understood that the present disclosure of the preferred form has been made only by way of example and that numerous changes in the details of construction and the combination and arrangement of parts may be resorted to without departing from the spirit and the scope of the invention as hereinafter claimed.

What is claimed is:

1. A high voltage switch including in combination a bracket, integral mounting lugs extending from said bracket and adapted to receive screws for mounting said bracket, a solenoid including a core having first and second extensions secured to first and second end portions thereof and movable therewith, a spring acting between said first extension and said solenoid for maintaining said core in its lowermost position in the de-energized condition of the solenoid, a pivot support integral with said bracket, a pivot member fixedly supported by said pivot support, a generally L-shaped contactor mounted on said pivot member for pivotal movement thereabout, an arm integrally connected to said contactor and extending from said pivotal connection, connection means connecting said solenoid core to said L-shaped contactor for moving same about said pivotal connection including an insulating member having first and second end portions, each said end portion having a slot therein, said slot in said first end portion of said insulating member receiving said second extension, a first pin securing said second extension in said slot, an arcuately shaped connecting link having first and second end portions, said slot in said second end portion of said insulating member receiving said first end portion of said link, a second pin pivotally securing said first end portion of said link in said slot, a third pin pivotally connecting said second end portion of said link to said arm, first and second arcuately spaced spring contacts located in the path of movement of the end portion of said L-shaped contactor, each of said contacts including a portion secured to said bracket

70
75

and a finger engaging said bracket, each said spring contact including a contact portion which is arcuate in configuration and lies in the arcuate path of travel of said end portion of said L-shaped contactor.

5 2. A switch including in combination a bracket, a solenoid including a core having first and second extensions secured to first and second end portions thereof and movable therewith, a spring acting between said first extension and said solenoid for maintaining said core in a first position in the deenergized condition of the solenoid, a pivot member supported by said bracket, a generally L-shaped contactor mounted by said pivot member for pivotal movement, an arm connected to said contactor, an insulating member having first and second end portions, means securing said second extension to said first end portion of said insulating member, a connecting link having first and second end portions, means pivotally securing said first end portion of said link to said second end portion of said insulating member, means pivotally connecting said second end portion of said link to said arm, first and second spaced spring contacts located in the path of movement of the end portion of said L-shaped contactor, each of said contacts including a portion secured to said bracket, each said spring contact including a contact portion which is generally arcuate in configuration and lies in the path of travel of said end portion of said L-shaped contactor.

10 3. A switch including in combination a bracket, a solenoid including a core, a spring for maintaining said core in a first position in the deenergized condition of the solenoid, a pivot member supported by said bracket, a contactor mounted by said pivot member for pivotal movement, an arm carried by said contactor, connection means connecting said solenoid core to said contactor for moving same including an insulating member having first and second end portions, means securing said core to said first end portion of said insulating member, a connecting link having first and second end portions, means pivotally securing said first end portion of said link to said second end portion of said insulating member, means pivotally connecting said second end portion of said link to said arm, first and second arcuately shaped spring contacts located in the path of movement of the end portion of said contactor, each of said contacts including a portion secured to said bracket, each said spring contact including a contact portion which is generally arcuate in configuration and lies in the path of travel of said end portion of said contactor.

15 40 4. A switch including in combination a bracket, a solenoid including a core mounted on said bracket, spring means for maintaining said core in a first position in the deenergized condition of the solenoid, electrically conductive pivot means supported by said bracket, first means for making electrical connection to said pivot means, an electrically conductive contactor having an end portion and mounted by said pivot means for pivotal movement thereabout, first and second arcuately extending spring contacts located in the path of movement of the end portion of said contactor and engaging the same in first and second positions respectively, second and third means for making electrical connection to said first and second spring contacts respectively, linkage means between said core and said contactor for moving the same about said pivot means, said contactor in said first position establishing a first electrical circuit between said first and second means and in said second position establishing a second electrical circuit between said first and third means.
